UNITED STATES PATENT OFFICE.

CHARLES FEATHER AND ARTHUR T. SAXTON, OF JAMESTOWN, NEW YORK.

DETACHABLE ICE-CREEPER.

SPECIFICATION forming part of Letters Patent No. 628,263, dated July 4, 1899.

Application filed September 30, 1898. Serial No. 692,356. (No model.)

To all whom it may concern:

Be it known that we, CHARLES FEATHER and ARTHUR T. SAXTON, citizens of the United States, residing in the city of Jamestown, in the county of Chautauqua and State of New York, have invented a new and useful Improvement in Detachable Ice-Creepers, of which the following is a specification.

The object of our invention is to make a strong and durable ice-creeper which can be easily and firmly attached to the shoe-heel and as easily removed and carried in the pocket when desired.

Our device consists of two parts. One is a small hooked plate which is permanently fastened to and worn on the heel, the hooked projection extending out therefrom in front of the heel. The other is a detachable part which is fitted to the front of heel and bottom of heel and instep and having spurs and a lever with an eccentrically-curved head to clamp under the hooked plate, all of which will be fully understood from this application and the accompanying drawings, in which—

Figure 1 is a perspective view of shoe-heel with the creeper attached, the front portion of the sole being broken away. Fig. 2 is a perspective view of detachable part of creeper and shows the form of the eccentrically-headed lever. Fig. 3 is a perspective view of shoe-heel with hooked plate set into the bottom of same in correct position. Fig. 4 is an end elevation of eccentrically-headed lever. Fig. 5 is a plan view of eccentrically-headed lever.

Similar numerals refer to similar parts in the drawings.

10 represents a boot or shoe heel, and 10' the front of same.

11 is a metal plate set in level with the bottom of the heel at its front edge and the hook 13, extending up in front of the heel, and is permanently fastened in place by screw 12. This plate might be made larger and more screws used, if needed, but one screw serves all common purposes. In the detachable part, Fig. 2, the two arms 14 14 extend back on the bottom of the heel and down in spurs 14' 14'. Parts 15 15 are bent at right angles from arms 14 14 to fit the front of heel 10' and form the opening 20 for hook 13. Parts 15 15 curve inwardly toward opening 20, the inner edges

being very thin to fit the eccentric head of lever 17. Part 16 extends at right angles from parts 15 15 along the instep just far enough to receive and lock spring-lever 17 in notch 19. Lever 17 is secured to part 16 by rivet 23 near its eccentrically-rounded head 21 22 and is bent up at 18 to obtain a finger-hold to snap it out and in notch 19. Any other finger-hold will do as well. The eccentrically-curved head or end 21 is turned up to form flange 22 to clamp under hook 13. This flange is cam-shaped at the top and on the inside curve 22' as well as the end 21 in order that this eccentricity may form a clamp under hook 13 to draw the detachable part firmly against the heel and instep, the top cam pressing against the hook at 13' and the inner curve 22' pressing against the point of hook to produce a double draw or clamp. This double draw takes place at the same time and is so gaged as to rigidly hold the creeper in place when lever 17 locks in notch 19.

To disengage the creeper, raise the spring-lever 17 out of notch 19 and turn at right angles, as shown in Fig. 2. This releases the lever-head from hook 13, and the creeper may be removed. To attach the creeper, place it in position and snap lever 17 into notch 19.

Having fully described our invention, what we claim as new, and desire to secure by Letters Patent, is—

1. A detachable ice-creeper, consisting of, a plate fastened to the shoe-heel and having a hooked projection extending beyond the inner edge of the heel and turned up toward the instep, a detachable plate provided with spurs, and having a lever for clamping said detachable plate to the shoe undersaid hooked plate; substantially as shown.

2. In combination with a detachable ice-creeper, a metal projection from the shoe-heel, a lever having an eccentrically-curved head for clamping under said projection to hold the creeper in place, substantially as shown.

3. In combination with a detachable ice-creeper, a metal projection from the shoe-heel, a lever having a cam-shaped end and a cam-shaped flange for clamping the creeper rigidly under said projection with a double draw, substantially as shown.

4. A detachable ice-creeper, consisting of,

a metal-plate fastened to the shoe-heel and having a hooked projection in front of the heel, an angular plate provided with spurs and an opening for said projection, a lever 5 fastened to said angular plate and means for locking said lever, an eccentrically-curved head on said lever for clamping said angular plate to the shoe, substantially as shown and described.

10. 5. A detachable ice-creeper, consisting of, metal plate 11 and means for fastening to the shoe, projection 13 from plate 11, metal plate 14 15 16 provided with spurs 14' 14' to engage the ice and opening 20 to receive projection 15 13 and the head of a clamping-lever, spring-

lever 17 provided with cam-shaped end 21 and cam-shaped flange 22 for clamping under said projection with a double draw, and notch 19 for locking said lever, substantially as shown and described and for the purpose 20 set forth.

In witness that we claim the foregoing we have hereunto subscribed our names in the presence of two witnesses.

CHARLES FEATHER.
ARTHUR T. SAXTON.
